for Glasses.

Primary Examiner—Robert C. Spangler

[57] CLAIM

The ornamental design for a bottle cover, as shown.

DESCRIPTION

FIG. 1 is a front perspective view of a bottle cover showing my new design;

FIG. 2 is a rear perspective view; and

FIG. 3 is a side view.

The broken lines showing a portion of a bottle are for the purpose of showing environmental use only.

FIG. 1

FIG. 2

FIG. 3
